(57) **CLAIM**

The ornamental design for an electrode, substantially as shown and described.

DESCRIPTION

FIG. 1 is a perspective rear view of an electrode.

FIG. 2 is a rear view of FIG. 1.

FIG. 3 is a front view of FIG. 1.

FIG. 4 is a left side view of FIG. 1.

FIG. 5 is a right side view of FIG. 1.

FIG. 6 is a top view of FIG. 1; and,

FIG. 7 is a bottom view of FIG. 1.

The broken lines in each figure depict features of the electrode that form no part of the claimed design.

1 Claim, 3 Drawing Sheets
